and Gerald A. Lingelbach, 2922 Graceland Way, Glendale, Calif.

Filed Oct. 4, 1965, Ser. No. 87,530

Term of patent 14 years

(Cl. D80—10)

The dominant features of our design reside in the portion shown in full lines.

This is a continuation-in-part of design application Serial No. D. 77,188, filed October 29, 1963, and now abandoned.

We claim:

The ornamental design for adjustable shelf for display cabinets or the like, as shown and described.
